United States Patent Office

Des. 221,330
Patented Aug. 3, 1971

221,330

WALL PANEL

Lester V. Ottinger, Danbury, Conn., and Donald F. Luebs,
Vienna, Va., assignors to U.S. Plywood-Champion
Papers Inc., New York, N.Y.

Filed June 17, 1970, Ser. No. 23,546

Term of patent 14 years

Int. Cl. D25—01

U.S. Cl. D13—1

FIG. I

FIG. 2

FIG. 1 is a top plan view of a wall panel.

FIG. 2 is an enlarged view of a section of said wall panel.

The thickness of said panel is of normal commercial thickness.

We claim:

The ornamental design for a wall panel, as shown and described.
